1 Claim

ABSTRACT OF THE DISCLOSURE

A submersible pump for use in oil wells and the like consisting of a housing adapted to be attached to a tubular delivery pipe to be lowered into a well and having an inlet opening, a driven auger enclosed in a tube integral therewith mounted rotatably within said housing, said auger tube having clearance from the housing walls to prevent friction and having its open ends communicating respectively with said inlet opening and said delivery pipe, and venturi means powered by the pump action to prevent leakage of pumped fluid around said enclosed auger within said housing.

This invention relates to new and useful improvements in pumps, and has particular reference to pumps of the submersible type commonly used in oil wells and the like. Such pumps must of course develop a high delivery pressure in deep wells to elevate the oil to the ground surface, and are also subject to considerable abrasive wear from the sand, grit and other solid impurities entrained in the oil. Accordingly, the principal objects of the present invention are the provision of a pump of the character described which is capable of developing the delivery pressures required with a structure much less complicated than has heretofore been required in pumps of this general class, and which has novel provisions for reducing the abrasive wear thereof by the foreign matter entrained in the oil.

My invention may be summarized as the provision of a pump consisting of a tubular housing having an outlet opening adapted to be interconnected with a delivery pipe to be lowered into a well to a point beneath the liquid level therein, and an inlet opening spaced apart from said outlet opening longitudinally of said housing, an auger mounted concentrically in said housing intermediate said inlet and outlet openings, said auger having an enclosing tube integral and concentric therewith, there being substantial annular clearance between said auger tube and said housing, means for driving said auger, and venturi members at the exit end of said auger and operable by the velocity of the oil as it emerges from said auger to tend to create an upward suction in the annular clearance space between the auger tube and the housing, thereby tending to prevent reverse flow of oil through said clearance space.

With the above described objects in view, as well as other objects which will appear in the course of the specification, reference will be had to the accompanying drawing, wherein:

FIG. 1 is a side elevational view of a submersible pump embodying the present invention, shown operatively attached to a delivery pipe.

FIG. 2 is an enlarged, foreshortened fragmentary sectional view taken on line II—II of FIG. 1, with parts left in elevation,

FIG. 3 is a sectional view taken on line III—III of FIG. 2,

FIG. 4 is a sectional view taken on line IV—IV of FIG. 2,

FIG. 5 is a sectional view taken on line V—V of FIG. 2,

FIG. 6 is a sectional view taken on line VI—VI of FIG. 2, and

2

FIG. 7 is a sectional view taken on line VII—VII of FIG. 2.

Like reference numerals apply to similar parts throughout the several views, and the numeral 2 applies to the pump housing. Said housing is in the form of a cylindrical tube, having a cap 4 threaded into its upper end, into which the delivery pipe 6 is in turn threaded, said pipe communicating with the interior of the housing. Said pipe of course extends to the ground surface, and serves to support and position the pump in an oil well or the like, it being understood that the pump is when in use lowered to a point beneath the liquid level in the well and thereby submerged in said liquid. At its lower end, housing 2 has a tubular extension 8 threaded therein, said extension having a large number of narrow apertures 10 formed therein to permit the entry of oil. At its lower end, extension 8 is threaded on the mounting ring 12 of a sealed electric motor 14, the drive shaft 16 of said motor extending upwardly into extension 8 coaxially with housing 2. In cap 4, there is mounted a check valve 18 adapted to permit upward flow of pumped liquid from the housing into delivery pipe 6, but to prevent reverse flow. Said valve is mounted on a stem 20 which is vertically slidable in a bearing sleeve 22 carried in cap 4 by a spider support 24, and cooperates with a valve seat 25 formed in a partition wall of said cap.

Mounted coaxially in housing 2, and extending substantially the full length thereof, is an enclosed pump auger 26 including a vertical shaft 28, helical auger flights 30 and 32, and an enclosing tube 34. Said shaft, flights and tube are essentially integral, comprising a unitary structure, although they may of course be formed separately and later assembled. Shaft 28 is journaled at its upper end in a bearing sleeve 36 supported axially in the housing by a spider support 38, and is similarly journaled adjacent its lower end in a bearing sleeve 40 supported axially in the housing by spider 42. Said shaft extends below bearing 40, and is connected to motor drive shaft 16 by coupling 44, so as to be rotatably driven thereby. Electric current is supplied to motor 14 by a moisture-proof electric cable 46 extending down from the ground surface, being affixed at intervals to delivery pipe 6 by clips 48, and to housing 2 by clips 50.

Auger tube 34 is open at both ends, so that oil or other liquid to be pumped can flow therethrough by passing helically about shaft 28 between flights 30 and 32, and the auger is turned in such a direction (clockwise as viewed in FIG. 5) that liquid trapped therein is forced to follow this upward path, due to the upward incline of the flights in a direction opposite to the direction of rotation, and due to the inertial tendency of the liquid to lag behind the speed of rotation of the flights. However, as the liquid approaches the upper end of the auger its rotational speed closely approaches that of the auger, due to the fact that auger tube 34 rotates with the flights, and the liquid is therefore not subject to the frictional "drag" which would occur if the auger flights rotated in a fixed tube, as in the usual auger conveyor. Therefore, in the upper portion of the auger, there is actually only a very slight lift imparted to the liquid as compared to the "lift" of the flights themselves. For example, while one rotation of the auger would cause a flight "lift" equal to the pitch of one of the auger flights, the liquid might be elevated only perhaps 5% of this amount, since it is rotating at perhaps 95% of the auger speed. For this reason, the pump can develop a very substantial delivery pressure, fully adequate to pump reasonably deep wells. This represents a substantial simplification over the usual multi-stage turbine impellers commonly employed in pumps of this general nature. A plurality of flights are preferable to a single flight in the auger, in order to provide better balancing of the operating load on said auger. While an

auger having two flights is actually shown, three or even four flights could be used if desired.

In order to alleviate the abrasive wear common in submersible pumps, resulting from sand, grit and other foreign matter often entrained in the oil, water or other liquid being pumped, an annular clearance 52 is provided between the exterior surface of auger tube 34 and the internal surface of housing 2, the thickness of said clearance being greater than the diameter of the largest particle of foreign matter likely to be encountered. This can be accomplished by making the radial thickness of said clearance greater than the width of the entry apertures of housing extension 8. This of course alleviates the abrasive wear as desired, but liquid could also flow from the top to the bottom of the housing through clearance space 52, thus short-circuiting the pump, if means were not provided to prevent this return flow. Ordinary types of seals such as gaskets, ring seals or the like, are not practical, since they involve relative movement of surfaces either contacting or nearly contacting each other, and would hence themselves be subject to abrasive wear.

In the present structure, the sealing problem is solved by leaving annular passage 52 entirely open, and providing means operable by the auger action to produce an upward suction in said passage, the suction in some circumstances producing an actual upward flow of liquid in said passage, but being at least sufficient to reduce downward flow in said passage to tolerable limits, whereby to provide pumping action of acceptable efficiency. To this end, the extreme upper end portion of auger tube 34 is conically reduced to provide a lip 54 which converges upwardly in the direction of liquid flow. Said lip rotates within an annular ring 56 fixed in housing 2 being conveniently formed as a part of an element including upper bearing sleeve 36 and spider 38. The central aperture of said ring is conical to conform with the outer surface of lip 54, but is spaced apart from said lip to provide a conical passage 58 therebetween, said passage communicating at its lower end with the annular clearance 52 between auger tube 34 and housing 2, and opening at its upper end into housing 2 above ring 56. Lip 54 extends flush with the upper face of ring 56.

In operation, the lip 54 reduces the diameter of the column of liquid within the auger tube as said liquid passes through said lip, with the result that as the liquid emerges from the upper end of said lip, it is caused by its high rotational speed, which as previously described may be nearly as great as the peripheral speed of the auger, to flow radially outwardly by centrifugal force, thereby passing with high velocity over the upper end of conical passage 58. This action, by the well known Venturi principle, creates a zone of greatly reduced pressure, on suction, in and immediately above the upper portion of passage 58, thus tending to draw liquid upwardly through annular clearance space 52, and combating the tendency of the pressure head in delivery pipe 6 to force liquid downwardly through said clearance space to short circuit the auger. As previously indicated, it is not essential that upward flow of liquid actually takes place in space 52, although this may occur especially when pumping against smaller pressure heads. It is necessary only that the suction be of sufficient magnitude that reduces any downward flow in space 52 to a sufficient degree that the pump can operate with a reasonable and acceptable degree of efficiency.

It is considered that the operation of the pump has been adequately described in connection with the foregoing description of its construction. It will be readily apparent that a pump has been produced which solves or greatly alleviates two of the most prevalent problems usually occurring in connection with submersible pumps for use in wells. First, it provides good delivery pressure with a structure far simpler, and hence far more economical, than the complicated structures usually employed, and second, it virtually eliminates abrasive wear by grit or other solid matter entrained in the liquid being pumped.

While I have shown and described a specific embodiment of my invention, it will be readily apparent that many minor changes of structure and operation could be made without departing from the spirit of the invention as defined by the scope of the appended claim.

What I claim as new and desire to protect by Letters Patent is:

1. A submersible pump comprising:

- (a) a cylindrical tubular housing having an inlet opening at one end thereof, and an outlet opening at its opposite end,
- (b) a helical auger enclosed coaxially within and affixed to an open-ended cylindrical auger tube, said auger tube being disposed coaxially within said housing intermediate the ends thereof for rotation on its axis, there being an annular clearance space between said housing and said auger tube,
- (c) means carried by said housing for rotatably driving said auger in a direction to impel liquid in said housing toward said outlet opening, and
- (d) means operable to produce a suction force at the end of said annular clearance space closest to said outlet opening, thereby tending to produce a flow of liquid in said clearance space toward said outlet opening, said suction producing means comprising cooperating members carried respectively by said housing and said auger tube whereby said annular clearance space is taperingly reduced in diameter at the end of said auger closest to said outlet opening, and wherein said housing immediately adjacent the reduced end of said clearance space is of greater internal diameter than the reduced end of said clearance space, whereby liquid emerging from said auger tube is forced radially outwardly at high speed by centrifugal force over the adjacent end of said clearance space, whereby to create a zone of reduced pressure or suction therein.
